BOWLING BALL SUPPORT

Samuel N. Glantz and Milton Glantz, Lincolnwood, Ill.,
(both of 1127 W. Division St., Chicago, Ill. 60622)

Filed Nov. 29, 1968, Ser. No. 14,719

Term of patent 14 years

Int. Cl. D21—03

U.S. Cl. D34—5

FIG. 1

FIG. 2

FIG. 3

FIG. 5

FIG. 6

FIG. 1 is a pictorial view of the bowling ball support showing our new design;

FIG. 2 is an end view of the bowling ball support;

FIG. 3 is a front view of the bowling ball support;

FIG. 4 is a rear view of the bowling ball support;

FIG. 5 is a top view of the bowling ball support; and
FIG. 6 is a top view of another embodiment of the
bowling ball support wherein the ball receiving portion
is a circular aperture.

We claim:

The ornamental design for a bowling ball support, as
shown and described.
